Primary Examiner — Joseph Kukella*Assistant Examiner* — Heather Ann Laaveg Wencel(74) *Attorney, Agent, or Firm* — Onofrio Law(57) **CLAIM**

The ornamental design for an angel ornament, as shown and described.

DESCRIPTION

FIG. 1 is a front elevation view of an angel ornament showing my new design;

FIG. 2 is a back view thereof;

FIG. 3 is a top view thereof;

FIG. 4 is a bottom view thereof;

FIG. 5 is a left side view thereof; and,

FIG. 6 is a right side view thereof.

The subject matter depicted in the dashed lines in FIGS. 1 and 2 are shown for illustrative purposes only and forms no part of the claimed design.
